DEPTH REGULATOR FOR FISH LURES

Jack C. King, 678 Massachusetts,
North Muskegon, Mich. 49445

Filed Apr. 3, 1969, Ser. No. 16,562

Term of patent 14 years

Int. Cl. D22—07

U.S. Cl. D22—30

FIG. 1

FIG. 2

FIG. 3

FIG. 4

FIG. 1 is a perspective view of a depth regulator for fish lures, showing my new design.

FIG. 2 is a top plan view of my new device.

FIG. 3 is a bottom plan view of my new device.

FIG. 4 is an end elevational view of the device as seen in FIG. 2.

I claim:

The ornamental design for a depth regulator for fish lures, as shown.
